ROCK DRILL

John C. Curtis, Claremont, N. H., assignor to
 Sullivan Machinery Company, a corporation of
 Massachusetts

Application May 5, 1938, Serial No. 206,193

8 Claims. (Cl. 255—45)

This invention relates to rock drills, and more particularly, but not exclusively, to improvements in the supporting and guiding structure and the associated feeding mechanism of a hammer rock drill whereby the drill hammer motor is supported, guided and fed in an improved manner.

An object of this invention is to provide an improved supporting and guiding structure for a hammer rock drill. Another object is to provide an improved rock drill feeding mechanism. Still another object is to provide an improved automatic feeding mechanism operated by a vibratory action set up within the drill hammer motor during operation of the latter for effecting drill feed. Yet another object is to provide an improved recoil resisting or checking means associated with the drill hammer motor for controlling the feeding movement of the latter. A further object is to provide an improved automatic vibration-controlled drill feeding mechanism having embodied therein improved reversible control means whereby the drill hammer motor may be fed selectively in opposite directions along the drill guide. A further object is to provide an improved automatic vibration-controlled feeding mechanism for a hammer rock drill wherein a sliding carriage mounted on a drill guide carries a ratchet-controlled, feed control sprocket engaging a relatively stationary chain secured to the drill guide. Still another object is to provide improved means for guiding the control chain with respect to the control sprocket whereby more than tangential operative engagement of the chain and sprocket is attained. Other objects and advantages of the invention will, however, hereinafter more fully appear in the course of the following description and as more particularly pointed out in the appended claims.

In the accompanying drawings there is shown for purposes of illustration one form which the invention may assume in practice.

In these drawings:

Fig. 1 is a view in longitudinal vertical section, with parts shown in side elevation, through a hammer rock drill constructed in accordance with an illustrative embodiment of the invention.

Fig. 2 is a longitudinally extending horizontal sectional view, with parts shown in plan, taken substantially on line 2—2 of Fig. 1, the drill hammer motor being removed and a portion of the trunnion support structure broken away to facilitate illustration.

Fig. 3 is a rear end elevational view of the improved rock drill.

Fig. 4 is an enlarged cross sectional view taken substantially on line 4—4 of Fig. 1.

Fig. 5 is an enlarged cross sectional view taken substantially on line 5—5 of Fig. 1.

Fig. 6 is a detail sectional view taken on line 6—6 of Fig. 5.

Fig. 7 is a detail sectional view taken on line 7—7 of Fig. 5.

Fig. 8 is a detail sectional view taken on line 8—8 of Fig. 5.

Fig. 9 is an enlarged detail sectional view taken on line 9—9 of Fig. 2.

Fig. 10 is a detail sectional view taken on line 10—10 of Fig. 9.

In this illustrative embodiment of the invention, the drill supporting and guiding structure, generally designated 1, and the associated feeding mechanism, generally designated 2, are shown embodied in a rock drill of the mounted hammer type, and in this instance, the feeding mechanism is operated and controlled by a vibratory action set up within a drill hammer motor, generally designated 3, during operation of the latter. It will be evident, however, that various features of the invention may be embodied in tools of various other types.

The drill hammer motor 3 is herein of a conventional design comprising a motor cylinder 4 having front and back heads 5 and 6 and containing a reciprocating hammer piston 7. The hammer piston has a striking bar 8 for delivering impact blows to the shank 9 of a usual drill steel 10. The drill steel shank is mounted in a conventional manner in a chuck 11 supported within a front chuck housing 12 secured to the front end of the motor cylinder 4. The rear head 6 carries a conventional throttle valve mechanism 13 for controlling the supply of motive fluid to the motor cylinder for effecting reciprocation of the hammer piston. As the construction and mode of operation of a drill hammer motor of the type disclosed is well known to those skilled in the art, further description of the structure and mode of operation thereof is herein considered unnecessary.

Now referring to the drill supporting and guiding structure 1, it will be noted that an elongated drill guide 14, in the form of a bar and of generally T-shaped cross section, has lateral top flanges 15, 15 and an upright bottom flange 16 arranged perpendicular to the plane of the top flanges, the bottom flange 16 having a polygonal bottom portion 17 shaped for reception in a vise-like clamp 18. This clamp comprises a clamping jaw 19 formed on a horizontal trunnion support 20 having at the side thereof opposite from said clamp a vertically disposed swivel plate 21 adapted to be clamped in the conventional trunnion clamp of a saddle mounting. Cooperating with the stationary clamp jaw 19 is a movable clamping jaw 22 (Fig. 4), and a bolt 23 is mounted in a bore in the trunnion support and has threaded thereon an adjusting nut 24 engaging the clamp 22 for adjusting the latter.

When the clamp is loosened, the drill guide bar 14 may be slid longitudinally into different positions with respect to the trunnion support and thereafter rigidly clamped in position on the trunnion support by tightening the clamping jaw 22. The polygonal bottom portion 17 of the guide has relatively inclined sides adapted to fit within opposed conical seats 25 and 26, in the clamp members 19 and 22, respectively, so that when the clamp is tightened, the drill guide is held rigidly in position both against longitudinal movement and lateral displacement with respect to the trunnion support.

The improved automatic drill feeding mechanism 2 associated with the drill supporting and guiding structure, comprises a sliding carriage frame 30 having bottom guideways 31 receiving the lateral flanges 15, 15 of the drill guide bar 14, so that the carriage is mounted on the drill guide bar for sliding movement longitudinally therewith. The carriage frame 30 is in the form of a casing and is provided with an internal chamber 32 within which a feed control means is arranged. Arranged in the casing chamber is a horizontal shaft 33 suitably journaled in ball bearings and having an integral chain sprocket 34, as shown in Fig. 5. Keyed to the shaft 33 is a sleeve-like hub 35 of a rotatable ratchet ring 36, the latter having internal ratchet teeth 37. Arranged concentrically within the ratchet ring 36 is a stationary pawl carrier 38 (Fig. 5) having a stub shaft 39 keyed to a detachable cover plate 40 of the carriage casing. This pawl carrier carries reversible spring-pressed pawls 41 and 42 (Fig. 6) engageable with the ratchet teeth 37, to control the direction of rotation of the chain sprocket 34. The pawls are herein preferably eight in number, four for controlling the direction of rotation of the sprocket 34 in one direction and four for controlling the direction of rotation of the sprocket in the opposite direction. For selectively rendering the sets of pawls 41 and 42 effective, a shifter annulus 43 is rotatably mounted within the casing bore on a circular projection 44 of the cover plate 40, and this annulus has recesses 45 (Fig. 7) to permit the pawls to move into engagement with the ratchet teeth, and an internal surface 46 of the annulus is engageable with the pawls for pressing the latter inwardly into their released position. For moving the shifter annulus 43 into its different positions, a lever 47 (Fig. 8) projects within a slot 48 in the annulus, and this lever is secured to a control shaft 49 rotatably mounted in the casing cover plate and having a conveniently located operating handle 50. Spring-pressed plungers 51 and 52 (Fig. 8) mounted within bores formed in the casing cover plate 40 are engageable with notches 53 and 54 on the annulus and shaft respectively for locking the parts in their different adjusted positions. The internal mechanism of the feed control means runs in a lubricant bath within the casing chamber 32 and the casing bore. The chain sprocket 34, as shown in Fig. 1, engages a feed control chain 55, and guide rollers 56 journaled on horizontal shafts 57 supported by the carriage casing guide the chain through the open bottom of the carriage frame and relative to the chain sprocket. The guide rollers are arranged with respect to the control sprocket to direct the chain partly around the sprocket so that more than tangential operative engagement therebetween is attained. The control chain 55 lies on the top of and extends longitudinally along the drill guide

bar 14, and the latter has an upstanding ledge-like projection 58 extending longitudinally along the top surface thereof and with which the chain engages for guiding the chain to maintain the chain in longitudinal alignment with the drill guide bar. As illustrated, the rear end of the control chain is secured at 59 to an adjusting screw 60 extending through an opening in a bracket 61 secured to the rear end of the drill guide 14. Threaded on the screw and engaging the opposite sides of the bracket are adjusting and locking nuts 62 for adjusting the screw 60 to vary the tension of the control chain. As shown most clearly in Fig. 9, the forward end 15 of the chain is secured at 63 to an upstanding projection 64 integral with the forward end of the drill guide bar 14.

The universal connection between the drill hammer motor and the sliding carriage 30 comprises a yoke-shaped frame 65 swivelly mounted at 66 on a vertical axis on the sliding carriage to swing horizontally with respect thereto in planes parallel to the plane of the drill guide bar. The yoke-shaped frame 65 is pivotally mounted 20 on a pin 67 arranged in aligned bores on the carriage frame, and this pin has a grasping knob 68 whereby the pin may be axially released from the carriage frame, thereby to enable detachment of the yoke-shaped frame 65 from its pivotal connection with the carriage frame. The arms 69 of the yoke-shaped frame have aligned openings for receiving a horizontal bolt 70 mounted in a transverse bore 71 in the rear head 6 of the drill hammer motor. The drill hammer motor is pivotally mounted on the bolt 70 for swinging movement in a vertical direction with respect to the sliding carriage and drill guide. It will be seen that the pivot pin 67 and bolt 70 cooperate to provide a universal pivotal connection between the rear end of the hammer motor 30 and the sliding carriage 30.

A drill steel centralizer or "spotting" guide is provided for guiding the drill steel during starting or so-called "spotting" of a hole, comprising, as shown most clearly in Figs. 9 and 10, a detachable frame 72 having guideways 73 slidably engageable with the top flanges 15, 15 of the guide bar 14 at the forward end of the latter. The centralizer frame 72 has upstanding hook-shaped guiding fingers or lugs 74 adapted to embrace the drill steel. The centralizer frame may be secured to the drill guide bar 14 by a transverse bolt 75 insertable through openings in the frame 72 and engageable with a transverse groove 76 in the projection 64. When the centralizer is in the position shown in Figs. 1 and 9, the hook-shaped portions of the guiding fingers 74 engage the opposite sides of the drill steel to hold the latter against lateral displacement and for supporting the forward end of the drill hammer motor during "spotting" of a hole. The centralizer may be readily detached from the drill guide bar 14 simply by removing the bolt 75 and sliding the frame 72 forwardly from the guide bar flanges 15, the lugs or fingers 74 being disposed in opposed relation and spaced a sufficient distance apart so that when the centralizer frame is turned and thereafter moved laterally, the centralizer may be released from the drill steel.

The mode of operation of the improved rock drill is as follows: The drill guide bar 14 may be set up at the working face by clamping the swivel plate 21 of the trunnion support 20 in the trunnion clamp of a saddle mounting, and the

guide bar may be adjusted longitudinally with respect to the work by loosening the clamp 18, and when in proper position may thereafter be firmly clamped in place. When the drill guide bar is in the desired location, the drill steel centralizer is placed with its guiding fingers 14 in proper guiding relation with respect to the drill steel 10 and attached by the bolt 75 to the forward end of the drill guide bar 14, in the manner shown in Fig. 1. The operator may then manipulate the throttle valve mechanism 13 to effect the supply of motive fluid to the drill hammer motor 3, to actuate percussively the drill steel. When the drill hammer motor is running to effect percussive actuation of the drill steel 10, the reciprocatory movement of the hammer piston 7 causes, due to the sudden reversal in the direction of movement of the piston, vibratory or recoil movements of the hammer motor alternately in opposite directions longitudinally thereof, as is well understood by those skilled in the art; resulting in alternating tendencies of movement of the hammer motor forwardly and rearwardly with respect to the drill guide bar. Movement of the hammer motor in the direction opposite to that in which it is desired to effect feed is checked automatically by the ratchet and pawl mechanism, the active pawls 41 engaging the ratchet teeth 37, automatically checking reverse movement of the hammer motor and freely slipping relative to the ratchet teeth, automatically to permit movement of the hammer motor in the feeding direction. When the shifter annulus 43 is in the position shown in Fig. 7, the control sprocket 34 is free to rotate in a counter-clockwise direction as viewed in Fig. 1, relative to the control chain 55, thereby permitting forward movement of the drill hammer motor along the drill guide bar 14, the control chain, as the hammer motor moves forwardly, effecting such counter-clockwise rotation of the control sprocket. Reverse rotation of the control sprocket is checked automatically by the pawls 41 engaging the teeth of the ratchet ring 36, and as a result, rotation of the sprocket in a clockwise direction as viewed in Fig. 1, is prevented. It will thus be seen that as the hammer piston 7 of the hammer motor reciprocates within the hammer motor cylinder 4 to actuate percussively the drill steel 10, the jars imparted by the hammer piston, due to the sudden reversal in the direction of movement thereof, cause the hammer motor to jump step by step in a forward direction along the drill guide bar 14, thereby feeding the drill steel toward the work. When "spotting" of the drill hole is completed, the drill steel centralizer is, of course, detached from the drill steel and guide bar. When the operator manipulates the handle 53, the shifter annulus 43 may be rotated to effect release of the pawls 41, shown in Fig. 7, and to permit the pawls 42 to move into engagement with the teeth of the ratchet ring 36. When the parts are in this reversed position, the control sprocket 34, as viewed in Fig. 1, is free to rotate in a clockwise direction, so that as the hammer piston rapidly reciprocates within the hammer motor cylinder the control sprocket is free to rotate in a reverse feeding direction relative to the control chain, due to the jars set up by the hammer piston, the active pawls 42 releasing automatically to permit free rotation of the control sprocket in the reverse feeding direction, as the hammer motor moves rearwardly along the drill guide bar, and holding automatically the control sprocket against rotation in the opposite

direction, i. e. a counter-clockwise direction as viewed in Fig. 1. When the shifter annulus 43 is moved into its intermediate position, both sets of pawls 41, 42 are free to engage the ratchet teeth; and as a result, the control sprocket 34 is locked against rotation in both directions, so that movement of the hammer motor along the drill guide bar is prevented. Due to the universal connection of the rear end of the drill hammer motor with the sliding carriage of the automatic feed, the hammer motor may be swung in a vertical direction relative to the drill guide bar into different angularly related drilling positions, as indicated in dotted lines in Fig. 1, and may be swung laterally relative to the drill guide bar into different angularly related drilling positions, as indicated in dotted lines in Fig. 2; and in any of these inclined drilling positions, the automatic feed is effective to feed the drill steel toward or from the work; it being understood that the front end of the hammer motor is supported at that time by engagement of the drill steel with the work. The drill holes drilled by the hammer motor in these relatively inclined positions are, however, of a relatively shallow depth, due to the gradual change in inclination of the drill steel as the sliding carriage of the automatic feeding means moves longitudinally along the drill guide bar. The main purpose, however, of the universal pivotal connection between the hammer motor and the sliding carriage is to permit the drilling of straight holes even when the drill steel 10 is bent or otherwise out of alignment.

As a result of this invention, it will be noted that an improved rock drill is provided having an improved supporting and guiding structure for the drill hammer motor and improved automatic feeding mechanism for feeding the hammer motor along the guide structure. It will further be noted that an improved drill feeding mechanism is provided which is operated and controlled by a vibratory action set up within the drill hammer motor during operation of the latter. It will still further be noted that by the provision of the improved control means of the chain and sprocket type and the novel arrangement of the chain sprocket and control chain, an automatic drill feed of an extremely simple and compact character is obtained. It will also be noted that by the provision of the universal pivotal connection between the drill hammer motor and the sliding carriage of the drill feeding means, holes may be drilled in relatively inclined positions with respect to the drill guide. It will further be noted that the improved rock drill is not only compact and rugged in construction, but is also relatively simple and inexpensive in design. Other uses and advantages of the improved rock drill will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, the combination with a support, of a motor slidably on the support and having jars imparted thereto, and a recoil resisting mechanism for said motor including a sprocket wheel rotatably carried by the motor

and a chain carried by the support and held against longitudinal movement relative thereto, said chain passing partly around said sprocket wheel in operative engagement therewith, stop means for preventing the rotation of said sprocket wheel in one direction to enable a step by step longitudinal movement of the motor in one direction, and means carried by the motor and engaging the chain for guiding the latter partly around said sprocket wheel.

2. In a drilling apparatus, the combination with a support, of a motor slideable on the support and having jars imparted thereto, and a recoil checking mechanism for said motor including a flexible element secured to the support against longitudinal movement relative thereto, a rotatable member carried by the motor and engaging said element for rotation due to the jars imparted to the motor, stop means for preventing the rotation of said member in one direction to enable a step by step feeding motion of the motor, and means carried by the motor and engaging said flexible element for effecting lateral displacement of the latter to the support during the feeding motion of the motor.

3. In a drilling apparatus, the combination with a support, of a motor slideable on the support and having jars imparted thereto, and a recoil resisting mechanism for said motor including a chain extending longitudinally of the support and secured thereto against longitudinal movement, a sprocket wheel rotatably carried by the motor in operative engagement with the chain, said sprocket wheel having a radial thrust imparted thereto due to its engagement with said chain tending to move the sprocket wheel away from the chain, stop means for preventing the rotation of said sprocket wheel in one direction to enable a step by step longitudinal movement of the motor in one direction, and means carried by the motor and engaging said chain for counterbalancing said radial thrust.

4. In a drilling apparatus, the combination with a support, of a motor slideable on the support and having jars imparted thereto, and a recoil resisting mechanism for said motor including an elongated element extending longitudinally of the support and formed with traction means, a member rotatably carried by the motor in operative engagement with the traction means of said element, said member having a radial thrust imparted thereto due to its operative engagement with said traction means, stop means for preventing the rotation of said member in one direction to enable a step by step feeding motion of the motor, and means carried by the motor and engaging said elongated element for counterbalancing the radial thrust imparted to said member.

5. In a drilling apparatus, the combination with a support, of a motor slideable on the support and having jars imparted thereto, and a recoil resisting mechanism for said motor including a chain extending longitudinally of the support, a sprocket wheel carried by the motor in operative engagement with said chain, stop means for preventing the rotation of said sprocket wheel in one direction to enable a step by step feeding motion of the motor, and means carried by the motor and guiding said chain into more than tangential operative engagement with said sprocket wheel.

6. In a rock drill, the combination comprising a guide, a hammer motor guided for movement

along said guide and in which longitudinal vibratory movements in opposite directions occur during running of the motor, and means operated by said longitudinal vibratory movements

5 for effecting feed of said hammer motor along said guide comprising a flexible element secured at its ends to said guide, a rotatable control member mounted on said guide for movement relative thereto with said hammer motor and engaging said flexible element so that the vibrations set up within said motor effect rotation of said control member, stop means for preventing rotation of said control member in one direction to enable step by step feeding motion of said motor, and means mounted on said guide to move relative thereto with said motor and engaging said flexible element at the opposite sides of said control member for effecting guiding of said flexible element into more than tangential operative engagement with said control member.

20 7. In a rock drill, the combination comprising a guide, a hammer motor in which longitudinal vibratory movements in opposite directions occur during running of the motor, said motor mounted on said guide for movement therealong,

25 and means operated by said longitudinal vibratory movements for effecting feed of said hammer motor along said guide comprising a flexible element secured to said guide, a rotatable control member disposed on a transverse axis and mounted on said guide for movement relative thereto with said hammer motor, said control member engaging said flexible element so that the vibrations set up within said motor effect

30 rotation of said control member, stop means for preventing rotation of said control member in one direction to enable step by step feeding motion of said motor, and means comprising a pair of rotatable guides disposed on opposite sides of said control member on axes parallel to the axis of rotation of said control member for effecting guiding of said flexible element into more than tangential operative engagement with said control member.

35 40 8. In a rock drill, the combination comprising a guide, a hammer motor in which longitudinal vibratory movements in opposite directions occur during running of the motor, said motor mounted on said guide for movement therealong,

45 50 and means operated by said longitudinal vibratory movements for effecting feed of said hammer motor along said guide comprising a flexible element secured to said guide, a rotatable control member disposed on a transverse axis and mounted on said guide for movement relative thereto with said hammer motor, said control member engaging said flexible element so that the vibrations set up within said motor effect rotation of said control member, stop

55 60 means for preventing rotation of said control member in one direction to enable step by step feeding motion of said motor, and means comprising a pair of rotatable guides disposed on opposite sides of said control member on axes parallel to the axis of rotation of said control member for effecting guiding of said flexible element into more than tangential operative engagement with said control member, said axes of said rotatable guides lying in a longitudinal plane parallel to the plane of said guide and the axis of

65 70 rotation of said control member being disposed in a plane parallel to said plane.
